UNITED STATES PATENT OFFICE

111,241

DESIGN FOR A GLASS SIPHON BOTTLE OR SIMILAR ARTICLE

Thomas D'Addario, Astoria, N. Y.

Application July 15, 1937, Serial No. 70,467

Term of patent 7 years

To all whom it may concern:

Be it known that I, Thomas D'Addario, a citizen of the United States, residing at Astoria, in the county of Queens and State of New York, have invented a new, original, and ornamental Design for a Glass Siphon Bottle or Similar Article, of which the following is a specification, reference being had to the accompanying drawing, forming part thereof.

Fig. 1 is a front view of a glass siphon bottle or similar article, showing my new design.

Fig. 2 is a top plan view thereof.

Fig. 3 is a section taken through the wall of the bottle on line 3—3 of Fig. 1.

The characteristic features of the design reside

in providing on a glass siphon bottle, a frosted glass band having straight parallel sides around the upper portion of the bottle with the space above the band having a highly polished reflective metal surface completely encircling the bottle and with lettering on the frosted band of highly polished reflective metal similar to the portion above the frosted band. The lettering shown on Fig. 1 of the drawing is merely illustrative.

I claim:

The ornamental design for a glass siphon bottle or similar article, as shown and described.

THOMAS D'ADDARIO.
